CLAIM

The ornamental design for a bean bag toss game with inlaid lighting, as shown and described.

DESCRIPTION

FIG. 1 is a perspective view of the bean bag toss game with inlaid lighting.

FIG. 2 is a top view of the bean bag toss game with inlaid lighting.

FIG. 3 is a front end view of the bean bag toss game with inlaid lighting.

FIG. 4 is a right side view of the bean bag toss game with inlaid lighting.

FIG. 5 is a left side view of the bean bag toss game with inlaid lighting.

FIG. 6 is a back end view of the bean bag toss game with inlaid lighting; and,

FIG. 7 is a bottom view of the bean bag toss game with inlaid lighting.

The broken line circle, in FIG. 2, depicts a portion of the bean bag toss game with inlaid lighting and forms no part of the claimed design.

1 Claim, 7 Drawing Sheets
